UNITED STATES PATENT OFFICE.

EDWARD A. EVERETT, OF LONG ISLAND CITY, NEW YORK, ASSIGNOR TO NANDE CORPORATION, A CORPORATION OF NEW YORK.

RAILWAY-RAIL-ENGAGING DEVICE.

Application filed June 15, 1925. Serial No. 37,396.

This invention relates to devices for use on railway rails and particularly such devices which are supported by means having rolling engagement with the rails. Those familiar with the art realize that in laying railroad track it is necessary to provide for the expansion of the rails due to temperature changes by inserting spacers from the top between the abutting ends of the rails while they are being spiked to the ties and bolted together by the fish plates, and while this is being done it has been found desirable and even necessary that various devices for use on the trackway be rolled along the rails. The spacers as usually constructed have an angular portion protruding above the face of the rail necessitating entire or partial lifting of these devices at each spacer. This is a very serious inconvenience especially when the device rolling along the rail is heavily loaded and is also especially objectionable in the case of power operated machines controlled by one man such as applicant's track drill disclosed in U. S. Patent 1,408,872, issued March 7, 1922, or in the power operated wrench disclosed in application, Serial No. 654,789, filed July 30, 1923, because in such cases one man is obliged to lift the machine at frequent intervals as it moves along the track and such difficulties tend to seriously interfere with the introduction of labor saving machines of this class. These machines, moreover, are arranged to operate upon the side of the rail at a predetermined height which is gaged by the rollers on the rail and may be required to operate with the rollers at any position on the rail; it is apparent that these end spacers in raising the machine changes its alignment with relation to the side of the rail necessitating a special adjustment at this point thereby causing delay and introducing unnecessary expense, besides rendering the machine unstable on the rail due to the tilting of one end at the point where it is in operation.

A principal object of this invention is to provide a means whereby the above mentioned difficulties of the prior art are obviated and by which a device having rolling engagement with a railway rail may be rolled along the rail and positioned accurately at any point thereon freely and without impediment by reason of the pro-

trusion of end spacers above the running face of the rail.

A further object of this invention is to provide a means of the type specified which will have rolling engagement with the rail only in so far as a longitudinal portion thereof is concerned which is not in alignment with a protruding end spacer, and another object of the invention is to enable machines having rolling engagement with the rail and a mechanism aligned with the rail to pass over the protrusions of end spacers without changing said alignment.

Other objects and advantages will appear as the description of the particular physical embodiments selected to illustrate the invention progresses, and the novel features of the invention will be particularly pointed out in the appended claims.

In describing the invention in detail and the particular embodiments selected to illustrate the invention, reference is had to the accompanying drawings, wherein I have illustrated particular preferred physical embodiments of my invention, and wherein like characters of reference designated corresponding parts throughout the several views, and in which: Fig. 1 illustrates a side view of a railway rail and protruding end spacer with a structure embodying my invention resting thereon;

Fig. 2 illustrates another physical embodiment of my means which is herein shown as a grooved wheel;

Fig. 3 shows a machine for drilling the web of a rail having a rolling engagement with the rail constructed according to my invention;

Fig. 4 shows a means of applying my invention to both rails of a track;

Figs. 5 and 6 show alternative means of securing rolling engagement with a rail embodying my invention;

Figs. 7 and 8 show another form of my invention securing rolling engagement with a rail having a clearance in the centre of the rail, and

Fig. 9 shows an arrangement of applying my invention with a pair of independent rollers.

Referring to the drawings, 11 and 12 are the ends of a pair of abutting rails which are spaced by the spacer 13, as shown in Figs. 1 and 2. The usual form of this spacer

is wedge shaped in the body between the rails with the top turned over at an angle to rest upon the head of the rail. The protrusion of this top above the rail offers an obstruction on the centre of the rail with the objections mentioned and it is the purpose of the invention to provide means for rolling a machine along the track without obstruction from these protrusions. These spacers 10 are placed between the rails when they are laid and are removed before trains are operated over the track.

One form of applying this invention is embodied in the roller 14 which, through its 15 axis 15, may support a frame or carriage. As shown in Fig. 2, this roller is provided with double flanges 16 and 17 such as would be used on a carriage arranged to roll upon one rail of the track. The face of this roller 20 between the flanges is provided with an annular groove 18 aligning with the vertical centre of the rail and with the turned over head of the spacer 13 which it passes over with a clearance as indicated in Fig. 2. The 25 conical flanges of the roller, it will be noted, pass over and bear upon the rounded corners of the rail head thus providing a clearance space between the rail and the centre of the roller. Other means for securing this result 30 are described hereafter.

In Fig. 3 the application of these rollers is shown to a machine for drilling the web of the rail and in which the drill is positioned with respect to the rail by the rollers 35 on the rail. In this construction the roller 14 supports a pair of side frames 21—21, one of which carries the bracket 22 supporting the motor 23 having the fly-wheel 25 and the shaft 24 which carries the belt pulley 26 and 40 which drives the pulley 28 by the belt 27. Pulley 28 by a train of gears enclosed by housing 29 and supported by bracket 30 operates the drill mechanism 31 and the drill spindle 33. The spindle 33, it will be noted, is positioned with respect to the web of the rail 45 by the roller 14 and the adjustable foot 32. The drill is fed to the rail by the operating handle 34. A drilling machine of this type is disclosed in U. S. Patent 1,408,872, issued 50 in my name on March 7, 1922.

The drilling machine is balanced to roll along the rail on a pair of rollers similar to 14 and may be used for drilling or similar purposes on a rail that has just been set up 55 preparatory to installation in the track and in which the rail spacers are in place. The machine, it will be observed, is free to roll along the rail from place to place without obstruction from the rail spacers and without changing the alignment of the drill with 60 respect to the rail when a roller is stopped over an end spacer at a drilling location.

In Fig. 4 my invention is adapted to single flanged rollers or wheels running on opposite rails and connected by the axle 41

such as may be used on hand cars or similar railroad vehicles. The annular groove 18 is provided in each wheel and clears the end spacers in each rail and adds greatly to the convenience in operating loaded hand cars 70 during the construction of a railroad.

In Fig. 5 another means of carrying out my invention is shown which, instead of using flanged rollers, uses a roller with a V groove as indicated at 42 which engages 75 the outer corners of the rail head and passes over the centre with a clearance.

In Fig. 6 a construction similar to Fig. 5 is shown but instead of using a V groove, a circular groove as indicated at 43 is used 80 which secures the necessary clearance in the centre of the rail head.

In Fig. 7 the desired results are secured by a built up roller comprising the discs 44 and 45 with the spacer 46 of smaller 85 diameter than the discs, thus securing the necessary clearance in the centre of the rail head.

In Fig. 8 the construction is somewhat similar to Fig. 7 with the discs 47 and 48 90 mounted upon the axle 49 and having integrally formed abutting spacers as shown which provide an enlarged clearance above the centre of the rail head.

The means shown in Fig. 9 for securing 95 the objects of the invention comprise a pair of inclined rollers 51 and 52 pivoted to the frame 50 with a clearance as shown above the centre of the rail head.

Although I have particularly described 100 the construction of physical embodiments of my invention, and explained the operation and principle thereof, nevertheless, I desire to have it understood that the forms selected are merely illustrative, but do not exhaust 105 the possible physical embodiments of the idea of means underlying my invention.

Having thus described my invention, I claim:—

1. In a machine having a tool for operating on a railway rail which must be accurately positioned longitudinally of the rail when in use, the combination of a device supporting the tool and movable along and at least partially supportable by at least one rail of the track having at an end of some rail section a projection extending above the top face of the rail; an in effect flanged wheel interposed between the device and the rail supporting the device and rollable on substantially a portion of the top face of the rails, said wheel intermediate its sides formed with a cut away portion whereby said wheel may pass substantially freely without impediment over said projection whereby entire or partial lifting of the device is avoided upon passing said rail end and the device may be accurately positioned at any desired point along the rail. 120

2. In a machine having a tool for operating

- ating on a railway rail which must be accurately positioned longitudinally of the rail when in use, the combination of a device supporting the tool and movable along and 5 at least partially supportable by at least one rail of the track having at an end of some rail section a projection extending above the top face of the rail; means interposed between the device and the rail supporting 10 the device and rollable on substantially a portion only of the top face of the rail, said portion being out of longitudinal alignment with the said projection whereby said wheel may pass substantially freely without im- 15 pediment over said projection whereby entire or partial lifting of the device is avoided upon passing said rail end and the device may be accurately positioned at any desired point along the rail.
- 20 3. In a machine having a tool for operating on a railway rail which must be accurately positioned longitudinally of the rail when in use, the combination of a device supporting the tool and movable along and 25 at least partially supportable by at least one rail of the track having at an end of some rail section a projection extending above the top face of the rail; means interposed be- 30 tween the device and the rail supporting the device and rollable on substantially a portion only of the top face of the rail, said portion being out of longitudinal alignment with the said projection and means to maintain proper coaction between said first mentioned means and the rails whereby said wheel may pass substantially freely without im- 35 pediment over said projection whereby entire or partial lifting of the device is avoided upon passing said rail end and the device may be accurately positioned at any desired point along the rail.
4. In a machine having a tool for operating on a railway rail which must be accurately positioned longitudinally of the rail when in use, the combination of a device supporting the tool and movable along and 40 at least partially supportable by at least one rail of the track having at an end of some rail section a projection extending above the top face of the rail; means interposed be- 45 tween the device and the rail supporting the device and rollable on substantially a portion only of the top face of the rail, said portion being out of longitudinal alignment with the said projection and means to maintain proper coaction between said first mentioned means and the rails whereby said wheel may pass substantially freely without im- 50 pediment over said projection whereby entire or partial lifting of the device is avoided upon passing said rail end and the device may be accurately positioned at any desired point along the rail.
- 55 Signed at New York, in the county of New York and State of New York, this 29th day of May, 1925.
- 60 EDWARD A. EVERETT.
